UNITED STATES PATENT OFFICE.

OTTO A. FREDERICKSON, OF WETHERSFIELD, CONNECTICUT, ASSIGNOR TO THE AMERICAN WIREMOLD COMPANY, OF HARTFORD, CONNECTICUT, A CORPORATION OF CONNECTICUT.

ELECTRICAL CONDUIT FITTING.

Application filed May 31, 1923. Serial No. 642,536.

This invention relates to those structures which are provided for enclosing electric circuit wires in buildings, and more particularly to the ornamental type of such structures which comprise a metallic base that is designed to be secured in place on the wall or ceiling of a building, and a sheet metal cap that is adapted to be sprung onto the base to form the enclosing wire-channel.

These conduits have straight running-sections of different capacities for different numbers of wires, and elbows for bends which may be flat on a ceiling or horizontal surface, or around the outside of a corner or inside of a corner of a wall or vertical surface. The ends of the running-sections are engaged with the bases of the elbows and the elbow caps are sprung over the ends of the running caps and onto the elbow bases when the installation is ready for service.

The object of the present invention is to provide an inexpensive, ornamental and easily manipulated construction for the elbow caps of such conduits whereby the elbow caps are readily adaptable to running caps of different depths.

This object is attained by making elbow bases and elbow caps of a single size having a capacity that will receive the largest desired number of wires, and forming at the ends of the elbow caps tongues which are bent inward so as to fit the small size running caps and close the openings at the joints, but which tongues may be readily broken off by any installer when necessary so that the elbow caps will fit the large size running caps, and thereby eliminate the necessity of manufacturing and keeping in stock and transporting different sizes of elbow caps.

In the accompanying drawings Figure 1 shows the ends of two running-sections of conduit connected by an elbow section constructed according to this invention, with a portion broken away to show the manner of making the joints between the elbow and a running-section of small size. Fig. 2 is a transverse section on the plane indicated by the dotted line 2 on Fig. 1. Fig. 3 shows the ends of two running-sections of conduit connected by an elbow section with a portion broken away to show the joint between the elbow and a running-section of large size. Fig. 4 is a transverse section on

the plane indicated by the dotted line 4 on Fig. 3. Fig. 5 is a side view on larger scale of the end of an elbow before the tongue is bent in or broken off. Fig. 6 is a plan view of the elbow end shown in Fig. 5 with the tongue out straight. Fig. 7 is a view looking at the end of the elbow with the tongue bent to position occupied when the elbow is to be used with a small size running cap. Fig. 8 is a plan view of what is shown in Fig. 7.

The running-sections of the conduit illustrated comprise a metal base strip 10 and a metal cap 11 which cap is stamped or rolled to channel shape of sheet metal that is usually somewhat lighter than the metal of the base strip. The cap is suitably finished on the exterior and its edges are so formed that they will snap over and clamp the edges of the base strip in order to hold the parts firmly together and form a rigid conduit. The running caps shown in Figs. 1 and 2 while of substantially the same cross-sectional configuration, are somewhat less in depth than are the running caps illustrated in Figs. 3 and 4, the larger size being used when more conduit wires are to be covered than can be conveniently accommodated in the smaller size.

The elbow is formed of an angular base strip 12 of relatively stiff metal and an angular channel shaped cap 13 stamped or folded to shape of metal thinner than the base strip. The elbow cap has substantially the same cross-sectional configuration and desirably has the same exterior finish as the running caps, and its edges are shaped to spring onto the edges of the elbow base and hold it in position. The elbow cap is made of a sufficient depth to receive the large size running caps. At the middle of each end of the elbow cap and integrally formed therewith is a tongue 14 the side edges of which are shaped to fit the interior of the side walls of the elbow cap while the end edge is shaped to fit the exterior wall of the top of the small size running caps.

In installing these conduits the elbow base is secured in position and the ends of the running-sections engaged therewith by passing the ends of the running bases over the ends of the elbow base and passing the edges of the ends of the running caps around the edges of the elbow base. The elbow cap is

then snapped in position on its base and over the ends of the running caps. If the running caps are of small size the tongues at the ends of the elbow cap are bent inward, 5 as illustrated in Fig. 7, and preferably they are thus furnished the installer by the manufacturer, so that the gaps between the top of the running caps and the top of the elbow cap will be closed, as illustrated in Figs. 10 1 and 2. Should the running caps be of large size the tongues at the ends of the elbow cap are broken off so that the elbow cap will fit the large size running caps closely when snapped to position, as illustrated in 15 Figs. 3 and 4.

By the employment of the improvement herein described it is only necessary to furnish one size of elbow for both large and small size running-sections, the tongues at 20 the ends of the elbow caps adding a very small percentage to the cost, thus making unnecessary the production of two different sizes of elbow caps with the incident expense to the manufacturer, and the necessity of carrying, both by the manufacturer and installer, elbow caps of two different sizes. The tongues formed at the ends of the elbow caps in the manner described are left bent in so as to close the gaps at the ends of the 25 30 elbows when the smaller size of running

caps are used, or they can be quickly bent out and easily broken off when it is desired to fit the elbow caps over running caps of the larger size.

The invention claimed is:—

1. An electrical conduit fitting comprising a base strip, a cap that is channel-shaped in cross section and has an area sufficient in size to receive a large size conduit, adapted to be applied to the base, said cap at its end 40 having an integral tongue that extends inwardly toward but not to the base strip, leaving an opening that is of sufficient size to receive a small size conduit, and said tongue being partially separated from the 45 cap whereby it may be broken away to produce an opening of sufficient size to receive a large size conduit.

2. A cap for an electrical conduit fitting, 50 said cap being trough-shaped in cross section and having at an end a tongue extending inwardly from its front face and leaving an opening into the end of the cap shaped to receive a conduit of one cross sectional area, said tongue being normally connected with the cap by metal of less resistance whereby it may be removed leaving an opening shaped to receive a conduit of larger cross sectional area.

OTTO A. FREDERICKSON.
